UNITED STATES PATENT OFFICE.

GEORGE W. McCONNELL, OF CARROLLTON, OHIO.

DESIGN FOR A BEARING-PLATE FOR VEHICLES.

SPECIFICATION forming part of Design No. 30,629, dated April 25, 1899.

Application filed March 24, 1899. Serial No. 710,371. Term of patent 14 years.

To all whom it may concern:

Be it known that I, GEORGE W. McCONNELL, a citizen of the United States, residing at Carrollton, in the county of Carroll and State of Ohio, have invented and produced a new and original Design for a Bearing-Plate for Vehicles, of which the following is a specification, reference being had to the accompanying drawings, forming a part thereof, in which—

Figure 1 is a front elevation of a bearing-plate for vehicles embodying the features of my design. Fig. 2 is a rear elevation of the plate shown in Fig. 1, and Fig. 3 is a vertical section taken practically on the line 3 3 of Fig. 1.

The design consists of a plate A, provided with a central rectangular opening B, and at one side of said plate a lug C is horizontally projected from the top and bottom walls of the opening B, the opposing surfaces of the lugs being respectively in the same plane as the upper and lower edges of the opening, and at the opposite side of said plate two opposing

lugs D are vertically projected, one from each side edge of the opening B, and the inner or opposing faces of the lugs D are in the same plane as the side edges of the opening. The lugs D are at right angles to the lugs C, and both pair of lugs are at right angles to the plate A. Each lug is provided with an opening E, extending through from one face to the other.

The leading feature of the design consists in a plate in which an opening appears, one face of which plate is provided with a horizontal lug at the top and a horizontal lug at the bottom of the opening, the opposite side of the plate having a vertical lug at each side of said opening in the plate.

I claim—

The design for a bearing-plate for vehicles, substantially as shown and described.

GEORGE W. McCONNELL.
